DESIGN FOR A FINGER RING

Otto Henry Mengel, Newark, N. J., assignor to
Acme Ring Co., Newark, N. J., a corporation of
New Jersey

Application April 30, 1940, Serial No. 92,043

Term of patent 3½ years

all whom it may concern:

Be it known that I, Otto H. Mengel, a citizen
of the United States and a resident of Newark,
the county of Essex and State of New Jersey,
have invented a new, original, and ornamental
design for a Finger Ring, of which the following
specification, reference being had to the accom-
panying drawing forming part thereof.

Figure 1 is a top plan view of a finger ring
owing my new design.

Figure 2 is a front elevational view of the ring.
Figure 3 is a rear elevational view of the ring.

Figure 4 is a side elevational view of the ring.
Figure 5 is an elevational view of the side of
the ring opposite that shown in Figure 4, and
Figure 6 is a fragmentary vertical sectional
view on the line 6—6 of Figure 1.

I claim:

The ornamental design for a finger ring, as
shown.

OTTO HENRY MENDEL.
